Ill., a corporation of Illinois

Application August 12, 1944, Serial No. 549,146

14 Claims. (Cl. 312—48)

1

The present invention relates to an improved dispensing apparatus generally operated or released for manual operation by a coin controlled mechanism to dispense articles one at a time, particularly bottles such as those used in handling soft drinks for public consumption.

Although the invention can be used equally well for dispensing uncarbonated drinks, it is particularly useful in dispensing bottled carbonated drinks since one of the features of the invention is the handling of a bottle with a minimum amount of agitation to the contents.

Not only does the invention handle a bottle with a minimum amount of agitation of the contents, but the invention is further characterized by a construction and arrangement of parts in which an unusually large number of bottles are handled with a minimum amount of danger of damage to the bottles, it being easy to place the bottles in their stored position ready for dispensing and at no time are the bottles handled violently during the dispensing operations.

In considering these advantages and objects of the invention, it will be appreciated by those who have had occasion to open carbonated beverage bottles that much of the carbonation of the drink is lost and sometimes part of the drink itself by the ebullition which occurs or is caused by handling a bottle violently enough to agitate the contents of the bottle prior to opening. This is particularly true where the drink has a great deal of sweetening in it or is supercharged with carbonated water to give the drink a dry taste.

Most bottles dispensed by a machine are opened by the purchaser at the machine with a cap lifter provided for that purpose. The lifter is fastened to the machine over a waste cap receptacle. The capped end of the bottle is inserted under the lifter and the body of the bottle forced downwardly. The position of the bottle prior to being forced downwardly is an upwardly inclined one as held by the hand, and one of the objects of the present invention is to deliver the bottle in approximately that position without prior agitation and for convenience in handling the bottle from the moment that it is made available by the dispensing apparatus. In delivering the bottle in this position with the least amount of agitation, the bottles are stored in vertical rows already disposed in this relative position from which the bottles may be slid axially along a short inclined path to their delivered position.

A further object of the present invention is to provide an improved construction and arrangement by which the bottles thus disposed may be

2

supported in large quantities around the periphery of a drum which can be step rotated to dispense the bottles one by one as controlled by a coin release mechanism.

5 A further object of the present invention is to drop the bottles one by one from the bottom of each vertical row with the least amount of violence or danger of breakage to the remaining bottles.

10 Another object of the invention is to utilize the general contour of bottles in handling vertically stacked bottles.

15 A further object of the invention resides in the elimination of the danger of breaking or chipping bottles which is incurred with conventional dispensing devices where the bottles have to be inserted at the top of the drum and lowered into place. With the present invention the replenishing bottles are inserted directly into the stacking channel in an upright position at the level immediately above the uppermost bottle in the channel and then tilted inwardly to lie in an inclined position.

20 A further feature of the invention resides in combining the advantages of a gravity delivery with the space saving accomplished by disposing the necks of the bottles inwardly where the geometric circumference narrows with a reduced radius and with the wide bottoms disposed outwardly where the geometric circumference of the drum is much greater.

25 The invention is further characterized by an improved device of the class described by which the bottles are dispensed one after the other from the bottom of the rows of vertically stored bottles in which the older bottles are dispensed before replenishing bottles are reached.

30 These being among the objects, further objects will become apparent from the claims, the drawings and the description relating to the drawings.

35 In the drawings:

40 Fig. 1 is a front elevational view of a bottle dispensing apparatus embodying a preferred form of the invention.

45 Fig. 2 is a vertical section taken upon the line 2—2 in Fig. 1.

50 Fig. 3 is a portion of the section shown in Fig. 2 enlarged to illustrate the manner in which the lowermost bottle is separated from the stack of bottles above it and released at the dispensing or discharge point.

55 Fig. 4 is a horizontal section taken through the cabinet illustrated in Fig. 1 with the section line through the dispensing drum stepped from the

top to the bottom thereof to show the sectional contour of the dispensing drum at different levels.

Fig. 5 is a perspective view illustrating the manner in which bottles remaining in the stack are lowered into position to bring the next bottle into dispensing position after the lowermost bottle has been discharged.

Before referring to the details of construction, it will be noted that the general construction is one in which a refrigerated cabinet 10 has a drum 11 mounted therein for rotation about a vertical axis upon a shaft 12. The periphery of the drum 11 is divided into a plurality of vertically disposed slideways in which bottles 13 are stacked in an inclined position with their bottoms disposed outwardly and their tops inwardly at a slant of approximately a 35° angle. The bottles 13 are dispensed one at a time from the bottom of the stacks through a discharge opening 14 as the drum 11 is rotated and indexed by an intermittent drive controlled by a coin release mechanism 15. The lowermost bottle in each row is brought successively into discharge position and released, while the bottles above the previously discharged bottle are lowered into place by a ramp mechanism 16.

As each bottle is discharged, it moves bottom first outwardly into the discharge opening 14 merely by sliding lengthwise a very short distance and without changing its relative inclined position. From the discharge opening the bottle can be picked up by hand. The contents of the bottle during the process are not agitated to any substantial degree from the time that the bottle leaves its position on the drum and the time that it has its neck inserted into the cap lifter 9.

The drum 11 comprises a top spider 17 and lower plate 18, (Fig. 2) with a cylindrical member 20 serving as an interconnecting spacer at the center and channel members 24 radially disposed about the member 20 secured at the top to the spider 17 and at the bottom to the plate 18.

The cylindrical member 20 is either formed of a casting, an extrusion or of corrugated sheet metal to provide therein circumferentially spaced vertically disposed grooves 21 which receive the tops 22 of the bottles 13 therein in guided relationship so that the tops of the bottles will slide down the cylindrical member when free to do so. The cylindrical member may be mounted in any suitable manner upon the spider and plate as by recesses 23 in which the ends of the cylindrical member 20 are received and held in indexed relationship therewith so that the spider and plate are located in predetermined positions with respect to the grooves 21.

The channel members 24 are shaped in cross section somewhat like a fanciful numeral "2" in which the top 25 is adapted to engage the bottom of the bottle to prevent it from moving radially outwardly and the bottom 26 serves to space the bottles circumferentially around the drum. The top 25 will be referred to as the retaining edge while the bottom 26 as the spacer. As shown, the two are parts of one member but it will be appreciated that they can be provided in two separate members.

Between the retaining edge 25 of one channel member 24 and the edge 27 of the spacer 26 of the next adjacent channel member is enough room to receive a bottle therethrough when the bottle is disposed in a vertical position. With this arrangement, vertically disposed bottles are inserted between the channel members at a point slightly lateral to the true radius of their testing

position until the side of the bottle is brought into engagement with the retaining edge of the channel member. The top of the bottle is then leaned inwardly to an inclined position in which the cap on the bottle engages in the corresponding groove 21 upon the cylindrical member 20. In this position the end 27 of the spacer 26 locks the bottle against displacement except in a vertical direction, thereby permitting it to slide up and down. The spacing between the retaining edge 25 and the groove 21 is such that the bottle is held in a position of approximately 35° angle. Thus the bottles can be inserted at any place along the channel 24 and tilted into position with a minimum amount of danger of breakage and the spacing between the retaining edge 25 and the groove 21 can be predetermined in relationship to the size of the bottle to be dispensed so that the invention can be arranged whereby any bottle having a bottom, sides and neck can be handled by such a dispensing device constructed to handle a particular bottle. The 35° angle is not critical since it may be and preferably is less where the bottle will slide out of position under its own weight when free to do so.

The upper ends of the channel members 24 are cut away as at 28 to secure maximum filling of the drum. The cutaways serve as an indication that the drum is full when the tops of the bottle stacks have reached that level. The remaining portion of the upper ends of the channel members are received in suitable sockets (not shown in detail) in the top spider 17 inside the axially disposed flange 30 provided on the spider 17, and the flange 30 is reinforced with a ring 31 having outwardly directed gear teeth 32 cut thereon (Fig. 4) to engage the teeth on the drive gear 33.

When disposed at 35° or less, the outward thrust of the bottles against the retaining edge 25 of the channel member 24 is not great, most of the weight of the bottles being directed vertically. However, to carry the outward thrust that is exerted at the bottom of the bottle, the channel members 24 are shaped so that they will not yield appreciably under this effort.

At the lower ends the channel members are cut away on the retaining edge 25 as at 34 up to a certain height to leave the spacer portion 26 to extend downwardly to be secured to the plate 18 in a suitable shake-proof engagement as hereinafter described with reference to bolts 37, this lower end of the spacer can be straight or curved inwardly, depending upon the fitting of the parts that is required to accommodate any particular bottle size for which the device is built to handle. Raised portions 35 may be provided upon the face 39 of the plate 18 to serve as guides or dividers receiving the bottles therebetween prior to discharge. However, as shown in Fig. 5, it is preferred to provide both the dividers 35 and also the extending lower portions of the spacer 26 by which the bottles are guided all the way from the top to and in position immediately above the plate 18, recesses 36 being provided in the front faces of the dividers 35 to receive the lower ends of the spacers 26 as held in place by bolts 37. The upper face of the plate 18 otherwise may be of any contour desired although it is preferred for purposes of convenience in handling the bottles that it be inclined also at a 45° angle.

The bottles do not normally rest against the face of the plate in the preferred form but rather the lowermost bottle has its lower bottom edge received in a cradle 38 formed on top of a lever 75 40 that is pivotally mounted as at 41 at the

periphery of the plate 18. Below the pivot 41 the lever 40 is provided with a weight 42 and by reference to Fig. 5 it will be seen that the effective supporting center of the cradle 38 is disposed to one side of the pivot 41 with the weight 42 disposed upon the other side of the pivot 41. The cradle 38 supports the base of the bottle above the face of the plate 18 as shown in Fig. 3.

A trip 43 is provided for the lever 40 and when the trip 43 engages the lower side of the lever 40 it moves the weight 42 further to one side of the pivot 41. With this movement the cradle 38 has an action which lowers the bottle as well as releases it. The lowermost bottle then drops against the face 39 of the plate 18. As the bottle is lowered a platform 47 supported on the cabinet 10 by brackets 47a catches the bottles above it and thereby frees the lowered bottle from the weight of the bottles above it so that it slides longitudinally through the discharge opening 14 immediately after it is released by the cradle 38.

By way of assisting the bottle to slide smoothly when the lever 40 is tripped, a faring member 44 is secured to the face 39 of the plate 18 with fingers 45 thereon curving upwardly and inwardly in the grooves 21 so as to serve as a guide for the cap of each bottle to prevent the cap from being torn loose in its movement or the neck of the bottle striking any portion of the mechanism which might cause it to chip or break. In accommodating the engagement of the platform 47 between the two lowermost bottles for the purpose mentioned, the shape or contour of the bottles themselves is utilized. The two lowermost bottles are cocked with respect to each other so that the belly of the bottom bottle supports the bottles above it and the upper side of the bottom bottle and the one above it are angularly separated as at 46 to receive the platform 47 between them. The platform enters the space 46 just prior to the tripping of the lever 40.

In cocking the two lowermost bottles to provide the space 46, the lower corner of the bottom bottle is disposed inwardly from a vertical projection of its preceding position in the rack with the neck of the bottle resting higher in its respective channel 21 than it otherwise would have occupied. This relationship is shown in Fig. 3 and is attained when the bottle is moved into position upon the cradle 38 after the preceding bottle has been discharged from the cradle. The platform 47 has a wing 48 thereon that directs the bottom of the bottle inwardly when it moves off of the platform 47 and into its new position on the cradle 38 as it is lowered into place by a ramp member 50 secured to the ramp 16 (Fig. 3). The edge of the adjacent spacer 26 guides the bottle downwardly in line with the cradle 38 while the wing 48 directs the bottle inwardly enough to catch in the cradle 38 as the bottle is lowered by the lowering ramp 50 which ramp eases the bottle, and the weight of all the bottles above it, downwardly into the new position upon the cradle 38.

The ramp 50 is pivoted at its upper end to the platform 47 to move upwardly to a horizontal position if upon occasion such is desired. Otherwise, the ramp 50 is held rigidly in position on the platform 47 by a stop mechanism 50a (Fig. 3) to carry the weight of the bottles as the bottom bottle slides down the ramp and gradually tilts with a rolling motion along its belly to separate as at 46 under the influence of the channel 21 and the wing 48 as the lower bottom edge moves slightly inward to catch upon the cradle 38.

The platform 47, the ramp 50 and the wing 48 are rigidly supported with respect to the cabinet 10 and as shown in Fig. 5 are shaped and constructed to cooperate with the drum when rotated in a clockwise direction as viewed in plan. Furthermore, the pivotal arrangement of the cradle 38 in relationship to the weight 42 is such that its operation to release and discharge a bottle takes place with the drum moved clockwise as viewed in plan. However, it will be appreciated that a reversal construction of these elements could be provided in event the drum was rotated in the opposite direction.

The trip 43 is also mounted upon the cabinet 10 and comprises a slide bolt located at a predetermined point to engage the lever 40 at a certain time in the sequence of operations so that the discharge of the bottle is accomplished in relationship to the rotation of the drum at that point when the bottom of the bottle registers with the discharge opening 14.

The drum 12 is mounted for rotation upon the shaft 12 by means of frictionless bearings and the shaft in turn is rigidly supported at its upper end by a bracket 51 secured to the top 52 of the cabinet 10 and at its lower end upon a three legged support one angle bar leg 53 of which is shown in Fig. 3 bar 53 secured to brackets 54 that are fastened to the sides 55 of the cabinet 10. The upper frictionless bearing 56 is a radial thrust bearing whose outer race is received in a socket 57 provided for that purpose in the spider 17 and the lower frictionless bearing 58 is an end thrust bearing whose outer race is carried in a socket 60 provided for that purpose in the plate 18.

As already mentioned, rotation of the drum is had in clockwise direction and is accomplished by means of the drive gear 33. The gear 33 is driven through a chain 61 from a manually operated gear 62 connected to a reciprocable handle 63 through a coin release mechanism so that when ever the proper coin is placed in the coin detector, full movement of the handle 63 will operate to rotate the drum on its back stroke a sufficient distance to bring about the discharge of the next bottle therein. The arrangement is such that the drum is indexed in its rotation the same number of degrees each time the handle 63 actuates it as exists angularly between the vertical rows of bottles. Counter-clockwise rotation of the drum is prevented by suitable means carried by the gear 33 such as a ratchet (not shown).

Below the bar 53 a blower 64 is provided which draws air down through cylinder 20 and forces it outwardly over the refrigerating coils 65 below the plate 18 to the outside portions of the cabinet 10. The refrigerated air is then forced upwardly through and over the bottles to be drawn back into the cylinder 20 for recirculation to cool the bottles. The plate 18 is thus formed for this purpose and the space between the plate 18 and the blower which is taken up by the bar 53 is confined by a sleeve 75 preferably formed integrally with the bar to reinforce it and to maintain this stream of circulation of the refrigeration air so that the bottles in the drum are subjected to a constant flow of cold refrigerant. With this arrangement the upper bottles which are generally placed in the drum more recently than the lower bottles are subjected to the cooling air at its lowest temperature, and suitable baffles to accomplish this may be provided such as the baffle 59 directing the cool air against the bottles.

The coils 65 are cooled by a condenser and

compressor unit (not shown) which is received in a compartment 66 and an extra supply of bottles is disposed in the lower portion of the cabinet as at 67 for precooling. The back 69 of the cabinet comes off by screws for installing and repairing the drum and a door 79 provides access to the precooling compartment. The body of the cabinet otherwise is made of inner and outer layers of sheet metal, or the like, and filled with insulation in a conventional manner.

Access is had to the drum to fill it through an opening 68 closed by a door arrangement 70 located at the front which arrangement comprises a double door; namely, an outer decorative shell 71 which covers the coin controlled mechanism and carries the discharge opening 14 having a rubber bumper 72 where it cushions the outward movement of a discharged bottle, and an inner insulated door 73 which provides access directly to the drum. With this arrangement the coin control mechanism is made available for repair or maintenance without losing the temperature in the cabinet 10 whereas if it is necessary to service the drum as by replenishing it with bottles, access can be had through the inner door 73. The opening 68 and door 73 are restricted to a width barely sufficient to expose only two stacks of bottles at a time and since the bottles are loaded at the level at which they will rest, the height of the opening 68 can be confined to that barely necessary to place the topmost bottle in place. This greatly strengthens the cabinet over conventional cabinets with large door sizes and also conserves refrigeration.

After the dispensing apparatus is installed and the refrigeration started, the two doors 71 and 73 are opened and the trip pin 43 removed from operation. From a supply of charged bottles on hand, the channel 24 or slideway on the drum nearest the opening can be filled clear to the top by quickly inserting each bottle vertically and leaning it inwardly. This shortens the filling time, speeds up servicing and increases the number of machines that can be serviced in a working day as limited only by the agility of the operator. When one row is filled, the drum is pulled to rotate clockwise. The lowermost bottle under these circumstances is the one resting upon the cradle 38 and this bottle passes under the platform 47, raises the ramp 50, the ramp 50 sliding between the two lowermost bottles as the drum is rotated. The second slideway is then charged with bottles and each successive slideway thereafter until the drum is completely filled. Thereafter the trip pin 43 is installed in its operative position and the doors are closed, the handle 63 when no coins are present being free to move back and forth and pass through the opening provided for its movement in the outer door 71.

Thereafter when the purchase price of one or more coins is inserted in the coin detector, movement of the lever will cause the drum to rotate to its next index point during which rotation the pin 43 will engage the lever 40 and move it in a direction to permit lowering the lowermost bottle slightly and permitting the bottle immediately above it to come to rest upon the platform 47 after which further movement of the lever 40 releases the lowermost bottle to allow it to drop off of the drum and into the chute leading to the discharge opening 14 through a normally closed door 49 which prevents dissipation of the cold air from the cabinet. Upon the second and all subsequent operations of the dispenser, the ramp

50 lowers the bottle resting on the platform 47 to its position on the cradle 38 as has already been described in which the spacer member 26 guides the bottle downwardly as it is eased by the ramp 50 and directed inwardly by the wing 48 into position on the cradle 38.

The wing 48 preferably does not engage the bottom of the bottle but only the outermost portion of the bottle as the bottle leaves the control 10 of the retaining edge 25 on the channel member 24. Thus the construction is such, including the pivotal mounting of the ramp 50, that the drum 11 can be released for clockwise rotation during loading operations without discharging bottles whenever the trip pin 43 is moved from its operative position. Consequently, once the doors are 15 opened to provide access to the drum for loading, the dispenser can be converted for loading and placed back into operation merely by moving the trip pin 43. Although the trip pin is slidably mounted for manual movement into and out of its operating position, the pin can be moved automatically if desired where the doors permit cooperation between them for that purpose. In 20 such an arrangement the trip pin can be a slide bolt which is urged to its release position by a spring 80 (Fig. 3) but held in its operative position by the outer door when the outer door is closed.

Consequently, from the description of the apparatus and its operation, it will be apparent that a dispensing apparatus is provided which can be loaded as fast as bottles can be handled by the service man and that the conversion of the apparatus for loading purposes as distinguished from dispensing purposes is reduced to a single adjustment which can be accomplished manually, or automatically if desired. Furthermore, the bottles when dispensed are handled with a minimum of agitation of the contents with a compact device made up of simple elements whose operations are readily understood by service men. It will also be appreciated that a power drive can be substituted for the manual drive represented if automatic operation is desired.

Consequently, having thus described the invention and a certain embodiment thereof, it will be readily apparent to those skilled in the art how the various objects are attained and that various changes can be made to accommodate articles of different sizes including bottled milk, uncarbonated beverage bottles and other articles very easily without departing from the spirit of the invention, the scope of which is commensurate 55 with the appended claims.

What is claimed is:

1. A bottle dispensing device including a drum having vertically disposed elements around the periphery of the drum, said elements being spaced from one another to define slideways for a series of bottles in each of them and being provided with means for obstructing outward radial movement of the bottles in the slideways, means 60 cooperating with the obstructing means to support the bottles in inclined positions one above another there being sufficient space between adjacent elements to insert the bottles vertically into the slideways prior to tilting them to their inclined position, a cradle means for supporting the bottom bottle at an acute angle to those above it immediately below said obstructing means and against axial displacement, means actuating said cradle as the drum is rotated for releasing the bottom bottle as the bottom bottle 65 approaches a discharge point, said cradle per-

mitting the bottom bottle to lower prior to the release of the bottle, and means for supporting the bottles above the bottom bottle when said bottom bottle is lowered prior to its release.

2. A bottle dispensing device including a drum having vertically disposed elements around the periphery of the drum, said elements being spaced from one another to define slideways for stacks of bottles in each of them and being provided with laterally extending portions obstructing outward radial movement of the bottles in the slideways, means cooperating with the portions to support the bottles in inclined positions one above another there being sufficient space between adjacent elements to insert the bottles vertically into the slideways prior to tilting them to their inclined position, cradle means for supporting the bottom bottle at an acute angle to those above it and against axial displacement below said portions, means for releasing the cradle as the drum is rotated as the bottom bottle approaches a discharge point, and means for supporting the bottles above the bottom bottle as said discharge point is approached.

3. A bottle dispensing device including a drum having vertically disposed elements around the periphery of the drum, said elements being spaced from one another to define slideways for the bottles in each of them and being provided with portions obstructing outward radial movement of the bottles in the slideways, means cooperating with the portions to support the bottles in inclined positions one above another with sufficient space between adjacent portions to insert the bottles vertically into the slideways prior to tilting them to their inclined position, a plate at the bottom of the drum having an incline under the influence of which a bottle thereon will slide off when free to do so, a cradle means and cupped raised portions carried on the plate for supporting the bottom bottle above the plate and at an acute angle to the bottles above it, said cradle holding the bottom bottle against axial displacement below said first named portions, means for removing the cradle as the drum is rotated from contact with the bottom bottle to allow the bottom bottle to lower onto a chute as the bottle approaches a discharge point, and means for supporting the bottles above the bottom bottle when said bottom bottle is lowered against said chute.

4. In an article dispensing apparatus, slideways for supporting bottles therein and having an effective horizontal dimension less than that of the bottle to dispose the bottles one above the other in an inclined position, a supporting structure for holding the bottom bottle in a position of greater incline from which the bottle will slide lengthwise under its own weight when free to do so, a releasable stop for preventing the bottom bottle's sliding lengthwise, and means for transferring a bottle from said slideway means to said supporting structure when said slideway means is moved relative to said structure.

5. In an article dispensing apparatus, slideway means for supporting bottles in an inclined position therein one above the other, releasable means for supporting the bottom bottle in a position of greater inclination from which the bottom bottle will slide lengthwise under its own weight when free to do so, means for tripping the releasable means to release said bottle at a discharge point, and means whereby the discharged bottle may be replaced with one from the slideway including a platform supporting the upper bottles in the slideway while the lower-

most bottle is discharged moving in a straight line along the long axis of the article and a ramp carrying the replacement bottle to a resting position on said releasable means when said last means and said first means are moved with respect to one another.

6. In an article dispensing apparatus, slideway means for supporting bottles therein in an inclined position one above the other, cradle means for supporting the lowermost bottle in a position of steeper inclination than that of the other bottles in the slideways from which position the lowermost bottle would slide lengthwise under its own weight when free to do so and in which position there is space provided between the two lowermost bottles in the slideways, means received in said space for supporting all the bottles above the bottom bottle when said bottom bottle is discharged including an inclined element for allowing the lowermost supported bottle to move to a resting position on said cradle means when said last means and said first means are moved with respect to one another.

7. In an article dispensing apparatus, a drum having a plurality of channels therein of a radial depth less than the height of the article to be dispensed whereby the articles are supported one above each other in an inclined position, means for supporting the lowermost article prior to discharge thereof in a position of greater inclination to provide a space between the articles at one end, and support means received in said space between the articles to carry the weight of bottles thereabove when the bottle therebelow is discharged as the drum is rotated.

8. In an article dispensing apparatus, a drum having a plurality of channels therein of a radial depth less than the height of the article to be dispensed whereby the articles are supported one above each other in an inclined position, cradle means for supporting the lowermost article prior to discharge thereof in a position of greater inclination to provide a space between the articles at one end, support means received in said space between the articles to carry the weight of bottles thereabove when the bottle therebelow is discharged, including a pivotally mounted ramp for permitting lowering of the next bottle onto the cradle means following the discharge of the preceding bottle thereon as the drum is rotated.

9. In a device for dispensing elongated articles, a drum having vertically disposed channel members defining slideways whose maximum dimension is less than the maximum length of the articles to support the article in an inclined position, said channel members being shaped and spaced from one another to provide openings between them throughout their length wide enough to receive said articles sidewise therethrough, and means for supporting the lowermost article in each slideway in weight supporting relationship for discharge at the bottom of said slideways.

10. In a device for dispensing soft drink bottles, a drum having vertically disposed channel members including vertical elements having laterally extending retaining edges at the periphery of the drum with spacers disposed inwardly thereof and a central element providing a vertically disposed groove, said elements defining slideways whose radial width is less than the length of the bottles whereby the bottles are supported in an inclined position, said elements being spaced to provide openings between them throughout their length wide enough to receive the bottles sidewise therethrough when the bottles are handled

in vertical position, and releasable means for supporting the bottom bottle in weight supporting relationship in said slideway.

11. In a dispensing device of the class described, the combination of a cabinet having a refrigerated compartment, a drum mounted for rotation about a vertical axis in the compartment, a plurality of vertically disposed elements having laterally extending edges and spaced circumferentially around the drum and defining vertical slideways of a radial depth less than the height of an article to be dispensed whereby the articles in the slideways are disposed in an inclined position, a cradle carried by and rotatable with the drum for supporting the lowermost article at an acute angle with respect to the article in the slideway immediately above it to provide a space between them at their outer ends, means carried by the cabinet for tripping said cradle to release the lowermost article whereby the article slides from the drum of its own weight, means for receiving an article sliding from the drum to deliver it outside of the cabinet in substantially the same inclined position, and means carried by the cabinet for supporting the articles in the slideway above the article being discharged at the time the article is discharged.

12. An article dispensing device comprising a cabinet having refrigerated compartment therein, a drum mounted in said compartment for rotation about a vertical axis, a plurality of elements having laterally extending edges and spaced around the periphery of the drum defining slideways of a radial depth less than the height of the article to be dispensed, said cabinet having an opening at one side of the drum, a closure for said opening, a coin control mechanism for rotating and indexing the drum with respect to said opening and, means for releasing the lowermost article in each slideway as the drum is successively indexed to bring successive slideways opposite the discharge opening.

13. A bottle dispensing apparatus including means for supporting a plurality of bottles in

side by side relationship to advance them successively to a point of discharge, means for supporting the first bottle to be discharged at an acute angle with respect to the next bottle to it to provide a space between the bottles at their bases, means for releasing the first bottle to permit it to be discharged at the point of discharge, and means receivable in said space to retain the remaining bottles in cooperation with the discharge means while the first bottle is being discharged and to permit the advance of said next bottle onto said supporting means after the first bottle is discharged.

14. In an article dispensing apparatus, slideways for supporting bottles therein one above the other in side by side relationship, a support for holding the bottom bottle in a position disposed at an acute angle to the upper bottles above it and at an angle of incline greater than the angle in which said upper bottles are disposed with respect to the horizon, at which angle the bottom bottle will slide lengthwise under its own weight when free to do so, a releasable stop at the lower of the two ends of the bottom bottle preventing the bottom bottle from sliding lengthwise, and a ramp for lowering a bottle onto said support when the slideways are moved relative to said ramp.
